UNITED STATES PATENT OFFICE.

FERDINAND C. ROBERTS, OF DETROIT, MICHIGAN.

TRANSPARENT SIGN.

Application filed September 25, 1922. Serial No. 590,482.

To all whom it may concern:

Be it known that I, FERDINAND C. ROBERTS, a citizen of the United States of America, residing at Detroit, in the county of Wayne 5 and State of Michigan, have invented certain new and useful Improvements in Transparent Signs, of which the following is a specification, reference being had therein to the accompanying drawings.

- 10 This invention relates to a transparent or translucent sheet of glass or other material having similar properties of a structure such that on viewing the glass from the front thereof, a certain word or other symbol is visible when the device is illuminated from the front only, and another word or symbol upon the rear surface of the glass is visible when the device is illuminated from the rear.
- 15 The primary object of the invention is to provide a device suitable for use in an automobile signal which normally by reflected light displays a word such as the name of the city or the make of the car and by transmitted light displays a signal such as "Stop," "Slow," "Right," "Left," or any other desired word or symbol.

In the drawing,

Figure 1 is a perspective view showing 30 the application of my device to a popular form of rear end automobile signal;

Fig. 2 is a front elevation of a sheet of material constructed in accordance with my invention;

35 Fig. 3 is a longitudinal section on the line III—III of Fig. 2, and

Fig. 4 is a rear elevation of the device shown in Fig. 2.

In Fig. 2 there is illustrated a preferred 40 embodiment of the invention in which a sheet of glass 1 is molded with raised letters 2 upon its front surface and raised letters 3 upon its rear surface. The glass 1 will preferably be of a red color when used as a stop 45 signal, though obviously the glass may be clear or of any other color than red that may be desired in any particular instance. Upon the front surface of the raised letters 2 there is applied a coating 4 preferably of a white 50 material capable of fusing and uniting with the material of the glass upon being heated to a sufficient temperature. This material may conveniently be applied by passing a roller coated with the proper material parallel with the body of the glass so as to come 55 in contact only with the members of the

outer face of the raised letters. The raised letters 3 of the rear surface of the glass preferably have their faces provided with serrations formed therein when the glass is 60 molded, the serrations preferably being arranged vertically in the letters at each end of the word and arranged diagonally in the intermediate letters, the diagonal serrations sloping downward away from the central 65 line of the plate as shown most clearly in Fig. 4. The entire surface of the rear of the glass surrounding the raised letters is preferably covered with some dark material capable when fused of uniting with the surface of 70 the glass and preferably being substantially opaque. The serrated faces of the raised letters are left clear. After being coated as described, upon opposite sides, the glass is 75 set within a kiln and the temperature is 80 raised to a point at which the material 4 upon the surface of the raised letters 2 and the opaque material 5 surrounding the raised letters 3 on the rear surface of the plate 1 become fused and permanently secured to the 85 glass.

When a piece of glass so prepared is placed 90 within a casing such as that shown at 6 in Fig. 1 with an electric lamp at the rear of the glass, the plate as seen by reflected light 95 appears dark with the raised letters 2 appearing white against the dark background. The white material 4 upon the surface of the letters 2 is preferably translucent so that when the lamp within the casing 6 is 100 lighted the letters 3 upon the rear of the glass appear as red against the dark background, the red light being visible through the translucent white material 4 upon the 105 raised letters 2.

By arranging the serrations as described, upon the raised letters 3 upon the rear of the glass, the light from the lamp within the casing 6 will be reflected to the right and left by the vertical serrations more strongly 110 than by the diagonal serrations, so that if the sign is viewed from an angle at one side or the other, the letters will appear bright because of the serrations and more uniform in brightness than if the serrations were all 115 diagonal.

While the letters upon the front and rear surfaces have been described as being raised and formed by molding, it is evident that they may be formed by other methods without sacrificing any of the advantages of the 120 invention. The invention is therefore

claimed broadly within the valid and legitimate scope of the appended claims.

I claim:

1. A sign comprising a sheet of translucent material having a design formed in relief upon the front face, the portion in relief differing in color from its surrounding portion by reflected light, the sheet having a design in relief on its rear face, the portion 10 in relief being translucent and the surrounding portion being opaque whereby the design in relief upon the rear face is visible from the front when illuminated from the rear.

2. A structure as in claim 1 in which the design in relief is provided with serrations, the serrations being substantially vertical at points remote from the center and lying at an angle downward away from the center line for portions of the design adjacent to the center.

In testimony whereof I affix my signature in presence of two witnesses.

FERDINAND C. ROBERTS.
